UNITED STATES PATENT OFFICE.

PETER BENDIXEN, OF DAVENPORT, IOWA, ASSIGNOR TO BETTENDORF COMPANY, OF BETTENDORF, IOWA, A CORPORATION OF IOWA.

JOURNAL-BOX LID.

Application filed January 3, 1922. Serial No. 526,698.

To all whom it may concern:

Be it known that I, PETER BENDIXEN, a citizen of the United States of America, residing at Davenport, Scott County, Iowa, ⁵ am the inventor of certain new and useful Improvements in Journal-Box Lids, of which the following is a true, complete, and concise description.

My invention relates to lids or covers for ¹⁰ journal boxes and the like and has as its objects the provision of a cover which shall be durable, convenient to assemble and use, and economical to manufacture. It also relates to an improved method of making ¹⁵ such articles.

The novel features of my invention are pointed out with particularity in the appended claims. The invention itself, however, will best be understood from the following description taken in connection with the accompanying drawing in which,—

Fig. 1 is a plan of a journal box lid according to my invention.

Fig. 2 is a section on the line 2—2 of ²⁵ Fig. 1.

Fig. 3 is a section on line 3—3 of Fig. 1.

Fig. 4 is a detail illustrating one of the strips from which the eye portions are formed as such strips appear before bending.

In the drawing, 1 is the body of the cover formed in one piece. A spring 2 is fixed to the body to hold the cover in the position in which it may be placed in use. A strap ³⁵ 3 assisted by the rivet 4 holds the spring in place. The rivets 5, 5 unite the strap 3 to body 1 as shown.

The body 1 is pressed from a blank of ⁴⁰ sheet steel and is substantially flat and has a downwardly extending flange 6 at each side designed to cooperate with upstanding flanges usually provided on the journal box. The flanges 6 also serve to stiffen the body of the lid. The body is further stiffened by ⁴⁵ depressions 7, 7 and 7^a pressed into it, and a finger piece 7^b is provided projecting from the front edge of the body for lifting the cover against the spring 2.

According to my invention, the rear edge ⁵⁰ of the blank 1^a (Fig. 4) from which the cover is formed is struck out to provide two spaced rearwardly extending strips, 8^a, integral with the blank and adjacent the rear corners of the blank. One of these strips ⁵⁵ appears in Fig. 4. Each of the strips 8^a

comprises a portion 8 bent in the same direction from body 1 as flange 6, but inclined outwardly somewhat away from body 1. Connected to part 8 is a flat shelf-like portion 9 adjacent the body of the blank and which extends rearwardly approximately in the plane of the edge of rim 6. Continuing rearwardly from part 9 as viewed in Fig. 4 each strip 8^a curves downwardly as indicated at 10. The curved portion 10 connects with a flat portion 11 which extends rearwardly in a plane parallel to the plane of body 1. At the rear edge of flat portion 11, each strip 8^a curves upwardly toward the plane of body 1 as illustrated at 12. The ⁶⁰ curved part 12 connects in turn with the short flat section 13. From the part or section 13 each strip 8^a bends sharply downward again, part 13 connecting with inclined part 14 which connects directly with ⁶⁵ the flat part 15, lying in the plane of flat portion 11. ⁷⁰

It will be seen, however, that parts 9 and 10 do not extend the full width of the strips. Part of the width of each strip 8^a in the ⁷⁵ region of parts 9 and 10 is taken up by a trough-like indentation 9^a pressed downward in the strip and adapted to act as a stiffening flute. This flute extends from the rear edge of inclined part 8 to the junction ⁸⁰ between curved portion 10 and the flat portion 11. A second stiffening flute 13^a is pressed in each strip 8^a in the region of sections 12, 13, and 14, and extends from the rear edge of the flat part 11 to the forward ⁸⁵ edge of the flat part 15. Flutes or indentations 9^a and 13^a are preferably in alignment. ⁹⁰

After the blank 1^a has been pressed up in the manner described, the strips 8^a are bent ⁹⁵ upwardly and forwardly upon themselves until the flat part 13 contacts with the flat part 9. In this operation the parts 9 and 10 are prevented from bending owing to the stiffening effect of flute 9^a, and parts 12, 13, ¹⁰⁰ 14 and 15 are prevented from bending by the flute 13^a. Hence all the bending is concentrated in what was originally the flat part 11 so as to form this section into a cylindrical eye 11^a. Moreover, when the flat ¹⁰⁵ portions 13 contact with the flat portions 9, inclined portions 14 contact with downwardly inclined sections 8 and the flat parts or lips 15 overlie and contact with body 1. The flat parts 13 and 9 are then connected ¹¹⁰

together and lips 15 are connected to body 1, these connections being made preferably by spot welds as indicated at 16, 16, but I do not limit myself to this.

5. It will be seen that eyes 11^a form convenient hinge sockets for the completed lid and that the channels or flutes 9^a and 13^a, but more especially flute 13^a, stiffen the connection between eyes 11^a and body 1 to prevent 10 the eyes being thrown out of proper position in any way after the device has been placed on a car.

It will be seen that a journal box lid according to my invention may be cheaply 15 and readily made from strong, durable material and that it is rigid and strong, but can be readily restored to its original shape if deformed.

Having thus described my invention, I 20 claim:

1. A journal-box lid comprising a body, and alined hinge eyes integral with said body and offset therefrom, the off-set portions intermediate said eyes and said body 25 being of double thickness, each thickness of

said off-set portions containing stiffening flutes and the layers of each of said doubled portions being connected firmly together.

2. A journal-box lid comprising a body, and alined hinge eyes integral with said body and off-set therefrom, the off-set portions intermediate said eyes and said body being of double thickness, each thickness of said off-set portions containing stiffening flutes and the layers of each of said intermediate doubled portion being welded together.

3. A journal-box lid comprising a body, and alined hinge eyes integral with said body and off-set therefrom, the off-set portions intermediate said eyes and said body being of double thickness and one of said thicknesses extending back onto said body, each thickness of said off-set portions containing stiffening flutes, and the layers of each of said intermediate doubled portions being welded together and said body being welded to said overlapping thickness.

PETER BENDIXEN.
